UNITED STATES PATENT OFFICE.

MINNIE E. SILVERTHORN, OF CAYUGA, NORTH DAKOTA.

HANDLE.

1,153,718.

Specification of Letters Patent. Patented Sept. 14, 1915.

Application filed March 20, 1915. Serial No. 15,759.

To all whom it may concern:

Be it known that I, MINNIE E. SILVERTHORN, a citizen of the United States, residing at Cayuga, in the county of Sargent and State of North Dakota, have invented certain new and useful Improvements in Handles; and I do hereby declare the following to be a full, clear, and exact description of the invention, such as will enable others skilled in the art to which it appertains to make and use the same.

This invention relates to handles adapted for attachment to various type of fabric articles, and more particularly a handle for attachment to mattresses for facilitating the moving or turning thereof.

The primary object of this invention is to provide a handle as specified, which includes a bail or handle member, a pair of base plates and a resilient wire bent to assume substantially a U-shape and having needle or inserting points formed upon the ends of its legs thereof, for insertion through the fabric of the mattress covering, for attaching the handle to the body, and further to provide receiving sockets in one of said base plates for receiving the inserting end of said needle.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:

Figure 1 is a perspective view of the improved handle, showing the same applied to a fragment of a mattress. Fig. 2 is a bottom plan view of the handle, showing parts thereof in section, and Fig. 3 is a cross sectional view through the handle on the line 3—3 of Fig. 1.

Referring more particularly to the drawing, 1 designates a mattress or similar article, which has a fabric covering. The handle structure indicated at 2, includes a pair of metallic plates 3 and 4, which have their facing edges spaced from each other, as is clearly shown in the drawing. The plate 3 has its marginal edges rolled upon themselves for clamping engagement with the apex of a U-shaped member 5, which is con-

structed of resilient wire or metal, and has inserting points 6 formed upon the ends of its legs 7 and 8, for facilitating the insertion of the legs through the fabric covering of the mattress 1. The plate 4 has its marginal side edges bent to form receiving sockets, indicated at 9 and 10, which are bulged outwardly as is indicated at 11, for receiving the enlarged inserting end 6 of the needles 7 and 8. The marginal end edge of the plate 4 is rolled upon itself for securing a rod 12 to the under surface of the plate, which rod is bent substantially equi-distant of its end to form a loop or U-shaped section 13, through which the end 14 of the bail or handle wire 15 passes. The end 14 of the bail wire 15 extends along the upper surface of the plate 4 to the inner edge of the same, where it is bent upon itself as at 15, and extends along the under surface of the plate 4, as is clearly shown in Fig. 2 of the drawing, for connecting the wire 15 to the plate 4. The bail wire 15 is bent to form a handle supporting section 16, upon which is mounted an ordinary cylindrical handle 17. The end 18 of the bail wire 15, is bent downwardly, and coiled upon itself about a hump 19 formed on the apex of the wire 5. The plates 3 and 4 are cut away, to permit of the extension of the hump or loop sections 13 and 19 outwardly therethrough.

In attaching the improved handle, to a mattress or the like, the needles 7 and 8 are sprung inwardly, as is indicated in dotted lines in Fig. 2 of the drawings, and outwardly out of the sockets 9 and 10, after which they are inserted through the fabric covering of the mattress as is indicated in Fig. 1, and they are again sprung for seating into the sockets 9 and 10, which securely connects the handle to the mattress, for facilitating the turning or moving of the mattress.

In reducing the invention to practice certain minor features of construction, combination and arrangement of parts may necessitate alterations to which the patentee is entitled provided such alterations are comprehended within the scope of what is claimed.

What is claimed is:

1. In a device as set forth, a substantially U-shaped wire having its legs sharpened to form inserting needles, the central portion of the wire of the U-shaped member being offset outwardly forming a bail retaining

loop, a plate carried by the apex of said U-shaped wire, said plate provided with an opening engaged over the loop formed in the bight portion of the U-shaped member, a bail wire looped in the bight portion of said U-shaped wire and extending longitudinally of the U-shaped wire and having its free ends bent for supporting a second plate, said second named plate having its marginal sides and edges bent upon itself for forming receiving sockets for the inserting ends of said legs, and a cylindrical handle mounted upon said bail members when in use.

2. In a device of the class described, a substantially U-shaped wire having its legs sharpened to form inserting needles, the bight portion of said U-shaped member provided with a centrally offset bail receiving loop, a plate surrounding the bight portion of the U-shaped member and extending for a short distance downwardly on the legs, said

plate provided with an opening to surround the bail loop formed on the bight portion of the U-shaped member, a bail wire connected to the loop in the bight portion of the U-shaped member and extending longitudinally thereof, its free end bent for supporting a second plate, said second named plate having its marginal sides bent upon themselves for forming receiving sockets, the outer extreme end being reduced to prevent the same from movement upon the pin when positioned thereupon, and a handle upon said bail member for carrying the same when in use.

In testimony whereof I affix my signature in presence of two witnesses.

MINNIE E. SILVERTHORN.
